United States Patent Office

Des. 179,766
Patented Feb. 26, 1957

179,766

SETTEE OR SIMILAR ARTICLE

Morris Futorian, Glencoe, Ill.

Application August 31, 1955, Serial No. 37,727

Term of patent 7 years

(Cl. D15—11)

Fig. 1 is a front perspective view of a settee or similar article showing my new design, and
Fig. 2 is an end view thereof.

The broken away portion shown in the drawing is to indicate indefinite length.

I claim:

The ornamental design for a settee or similar article, as shown and described.
